O. R. JONES.
CHECK PROTECTOR.
APPLICATION FILED MAY 24, 1920.

1,390,620.

Patented Sept. 13, 1921.

INVENTOR,
Orton R Jones
By *John R. Jones*
HIS ATTORNEY.

UNITED STATES PATENT OFFICE.

ORTON R. JONES, OF MONROVIA, CALIFORNIA.

CHECK-PROTECTOR.

1,390,620.

Specification of Letters Patent. Patented Sept. 13, 1921.

Application filed May 24, 1920. Serial No. 383,828.

To all whom it may concern:

Be it known that I, ORTON R. JONES, a citizen of the United States residing at the city of Monrovia in the county of Los Angeles, State of California, have invented new and useful Improvements in Check-Protectors, of which the following is a specification.

My invention relates primarily to a means 10 to protect checks taken from a pocket check book and the object thereof is to provide a device which can be readily placed upon a pocket check book and used to protect checks taken therefrom, and when the book is used 15 up can be placed upon another book.

In the drawings forming a part of this application Figure 1 is a view of a pocket check book with my check protector in position thereon to protect a check drawn for 20 \$40.00. Fig. 2 is a section on the line 2—2 of Fig. 1. Fig. 3 is an end view of Fig. 1.

Referring to the drawings, 5 is a pocket check book composed of checks, 6 provided with stubs 7. On the ends of the checks 25 adjacent to the stubs are vertical rows of figures indicating dollars. The first row of figures begins just below the word "Pay—Order" and is composed of 1—3—5—8—10—12. The next row begins with 15 and 30 the numbers increase by 5. Other rows can be added as desired. On the face of the check when the blank check is printed is a line as follows: "Pay no more than amount indicated in left." The words "Void if margin is detached" are also printed on the face. The protector is composed of the base 35 plate, 8 having a rib 9 with an enlarged round end 10 and lugs 11 projecting from the ends at the rear edge thereof. A back 40 strip 12 has its ends turned at right angles to the main portion. These ends are provided with apertures 13, in which are received lugs 11, and the pocket check book is slipped between plate 8 and strip 12, and 45 has a sliding fit therebetween. Mounted

upon plate 8 is the cutter blade 14 which has a portion near the rear edge bent to fit over rib 9 to keep the cutter from separating from the plate. The cutter has a stop lug 15 at the upper end which engages the ends 50 of strip 12 to keep the cutter from being drawn off the plate. At the lower end is an operating lug 16 to facilitate the moving of the cutter.

With a check book of this character of 55 blank checks carried in the pocket the drawer of a check can always protect his checks from being raised by severing from the check all numbers above the largest amount of dollars for which the check is 60 drawn. As illustrated in the drawings the device is so positioned that a check can be severed along the edge of the cutter so that when delivered 40 will be the highest number on the check which shows that it was 65 drawn for not over \$40.00.

After each check is drawn the slots in the ends of the back strip permits the other parts of the device to be lowered upon the other checks after the stubs are withdrawn. 70 It will be understood that the back strip is of resilient metal so that the ends may be sprung over the lugs of the back plate.

Having described my invention, I claim:

A check protector for checks having vertical rows of figures indicating various amounts in dollars, said protector including 75 a base plate having lugs at the ends thereof and a longitudinal rib with an enlarged head, a back strip having ends turned at 80 right angles to the main portion, said ends having apertures therein in which are received the lugs of the base plate; and a cutter plate having a portion bent to fit upon the rib of the base plate and a stop lug at 85 its upper end.

In witness that I claim the foregoing I have hereunto subscribed my name this 12th day of May, 1920.

ORTON R. JONES.
